UNITED STATES PATENT OFFICE.

EDWARD L. WILLIAMS, OF SANTA CRUZ, CALIFORNIA, ASSIGNEE OF ONE-HALF TO
AMOS A. WYCKOFF, OF SANTA CRUZ, CALIFORNIA.

LOCK.

1,093,817.

Specification of Letters Patent. Patented Apr. 21, 1914.

Application filed January 20, 1913. Serial No. 742,987.

To all whom it may concern:

Be it known that I, EDWARD L. WILLIAMS, a citizen of the United States, residing at Santa Cruz, in the county of Santa Cruz 5 and State of California, have invented certain new and useful Improvements in Locks, of which the following is a specification.

This invention relates in general to locks and more particularly to locks adapted to 10 receive a key at one end only, such locks being designed to permit the insertion and removal of a key only when the lock is in locked position and to prevent removal of the key when the lock is unlocked, such locks 15 being adapted for use on cash boxes, lockers, and the like.

Owing to imperfections in the construction of a lock or inaccuracies in its operation, it sometimes happens that the lock will be 20 unlocked by the removal of the key, particularly if the key sticks and is wiggled or moved about in an endeavor to withdraw it. The result is that the key is withdrawn while 25 the lock is unlocked instead of being locked as it is intended to be and should be.

My present invention is designed to positively lock the lock in locked position and initiate the removal of the key so that it will be impossible to unlock the lock when the 30 key is withdrawn.

One preferred embodiment of my invention is illustrated in the accompanying drawings and described in the following specification, while the scope of the invention 35 is set forth in the appended claim.

Referring to the drawings—Figure 1 is a side view of a lock embodying my invention; Fig. 2 is a view looking toward the left in Fig. 1; Fig. 3 is a plan view; Fig. 4 40 is a longitudinal sectional view of the lock; and Fig. 5 is a view taken substantially on the line 5—5 of Fig. 4.

The lock as shown in the drawings comprises a housing or casing 6 substantially 45 cylindrical in cross-section adapted to be set in the movable wall 7 of a box, locker, or the like, with its front face flush with the outer face of the wall in which it is set to receive the key 8 in the usual manner. A 50 cylinder 9 is rotatably mounted in the casing and carries on its top a lug or projection 10 secured thereon by screws 11 or other preferred fastening means, said lug being adapted to engage behind a lip or stop 12 of 55 the stationary wall 13 to lock the wall 7

thereto. The wall 13 is provided with a slot to permit the entrance and withdrawal of the locking lug 10 when the cylinder 9 is turned to unlocked position as shown by dotted lines in Fig. 2, the locked position of the lug being shown in full lines in Fig. 2. The casing is provided with a slot 14 which permits limited rotation of the cylinder to dispose the lug 10 in locked and unlocked positions.

An extension 15 on the bottom of the casing is provided with a plurality of sockets 16 adapted to contain the plungers 17 normally urged upwardly toward the cylinder by expansion springs 18. The cylinder is bored to receive tumblers 19 which are forced down into the position shown in Fig. 4 upon the insertion of the key 8, thereby depressing the plungers 17 to a position outside the periphery of the cylinder so that the cylinder can be turned to unlock the lock. The mechanism thus far described is of well known construction and is shown merely for purposes of illustration since it will be obvious that my invention, when better understood, is applicable to locks of other types as well as to the type above described.

Locks of this general character are designed to permit withdrawal of the key only when the lock is in locked position and to prevent withdrawal of the key when the lock is in unlocked position, but, owing to imperfections in construction and inaccuracies in operation, it sometimes happens, particularly if the key sticks in the lock, 80 that the lock will be unlocked in the operation of withdrawing the key with the result that the desired protection is lost. I have, therefore, designed a structure for positively locking the cylinder 9 against rotation in 85 the casing whenever the lock is turned to locked position so that all danger of releasing the lock upon withdrawal of the key is obviated. This locking device consists of a latch 20 pivotally mounted at 21 upon 90 the casing 6 and provided with a downwardly extending tail 22 adapted to be normally urged outwardly by an expansion spring 23 located in the housing, as shown in Fig. 2. The latch is provided adjacent its upper end with a tooth or dog 24 to engage 95 in a notch 25 in the rear end of the casing 6 and between this end and the pivot 21 with another tooth or dog 26 adapted to engage 100 in a notch or groove in the rear end of the 105 110

cylinder 9. Whenever the lock is turned to locked position the spring 23 will swing the latch about its pivot to engage both of the teeth with their respective notches, thereby 5 securely locking the cylinder against rotation in the casing. When the cylinder is thus locked it is impossible to turn it to unlock the lock until the latch has been released and this can only be effected by the 10 complete insertion of the key so that its inner end engages the latch and moves it outwardly into the position shown in full lines in Fig. 2 and in dotted lines in Fig. 1. When the lock is locked the key will be 15 forced outwardly by the spring-pressed latch into the position shown in full lines in Fig. 1; so that the cylinder will be immediately locked by the latch against rotation. Any manipulation of the key by twisting it or 20 wiggling it about in the key-hole to withdraw the same can not possibly release the latch which will positively hold the cylinder against rotation until the key has been again inserted its full length to move the 25 latch into inoperative position.

It is believed that my invention will be understood from the foregoing without further description and it will be manifest that I have provided a means for positively insuring against the accidental unlocking of a 30 lock of the general character disclosed, but, while I have shown in the drawings and described in the preceding description that

practical embodiment of my invention which at the present time seems preferable, nevertheless, I desire it to be understood that my invention is not limited in its application to the particular construction shown and described but is capable of embodiment in various forms within the purview of the following claim. 35 40

I claim:

A lock comprising a casing, a key cylinder rotatably mounted therein and provided with a longitudinally disposed key slot, a 45 notch formed on the inner end of said cylinder at one edge of said key slot, a notch formed in said casing at the inner end of said cylinder and diametrically opposite from said notch in the cylinder, a latch pivotally mounted in the casing at one side of said cylinder and adapted to overlie the end of said cylinder, dogs carried by said latch in position to engage in said notches whereby to lock the cylinder against rotation in the 50 casing, and a spring housed in said casing and adapted to urge said latch into operative position, the latch being disposed across the end of the key slot when the cylinder is in locked position, to be engaged and released 55 by a key projected through said slot.

EDWARD L. WILLIAMS.
